EXPANSIBLE AND REVERSIBLE ENVELOPE

George E. Powell, Los Angeles, Calif.

Application June 2, 1941, Serial No. 396,304

6 Claims. (Cl. 229—73)

This invention relates to improvements primarily in mailing wrappers herein specified as an envelope. The chief use of the envelope is to facilitate the sending of first class and lower class mail in combination in a single item thus insuring the receipt of both pieces of mail of the two classes at the same time to the avoidance of the annoyance of receiving the first class item and having to wait for the other to arrive. While, as stated, this is the primary purpose of the invention, yet the use of the latter is readily extensible to such purposes as transmitting drawings, documents, photographs and an indefinite list of sundry articles and materials.

Another phase of the invention takes into account the fairly common occurrence of the recipient of an item of mail lacking an adequate wrapper in dispatching a response, either from the standpoint of transmitting a letter or return-merchandise sent for inspection or approval. The difficulty thus engendered is overcome by making the instant envelope reversible in character. It is proposed to use a stout paper in the first instance so that the item of mail will not only withstand the wear and tear of the out-bound trip but will also withstand the reversal of the parts of the envelope and then the ultimate return trip.

Sight has not been lost of a desirable economy in the manufacture of the envelope. Toward this end it has been found that a basic pattern could be employed for all of the various purposes herein contemplated, the usual distinction generally occurring consisting of slight differences in the cuts of the flaps to vary the capacity of the envelope. With this preamble in mind the objects of the invention are as follows:

First, to provide an envelope which has a basic pattern and which is convertible into an all-purpose envelope mainly by altering the positions of the side flaps when closing said envelope for the purpose of mailing.

Second, to provide an envelope which according to a single type will suffice for first, second, third or fourth class mail, varying only in differences of size and thus avoiding the necessity of having to stock different types for the purposes stated.

Third, to provide an envelope in which first and other class mail can be sent at one and the same time, thereby enabling the expeditious transmission of a first class letter as well as matter such as samples, said envelope then being reversible by the recipient for the dispatching of a return letter by first class mail, or the return

of the other class of matter in its respective class by proper arrangement of the positions of the side and end flaps.

Fourth, to provide an envelope with the foregoing characteristics, having places at definitely indicated points for starting the opening operation, the guidance thus afforded preventing the mutilation of the envelope so that it can be reused as intended.

10 Fifth, to provide an envelope having corner fillets which reinforce the body and flaps when the enclosed matter is thin and which enable the expansion of the covering structure when the enclosure is thick.

15 Other objects and advantages will appear in the following specification, reference being had to the accompanying drawing, in which:

Figure 1 is a plan view of a characteristic blank, this view illustrating the appearance of the outside of the blank for the first form of the envelope.

Figure 2 is a plan view of the inside of said blank.

Figure 3 is a plan view illustrating the first 25 fold of the blank in Fig. 2, preparatory to constructing an enclosure for first and third or fourth class mail in a single mailable item.

Figure 4 is a plan view illustrating the second fold.

30 Figure 5 is a plan view illustrating the final fold whereupon the item is ready for mailing.

Figure 6 is a plan view of the envelope, showing it as having been opened at its destination.

Figure 7 is a plan view of the blank in Fig. 6, 35 showing said blank as having been flattened out and turned over preparatory to remailing.

Figure 8 is a plan view illustrating the first and second folds of the blank in Fig. 7.

Figure 9 is a plan view illustrating the final 40 and resealing fold of the blank in Fig. 7.

Figure 10 is a plan view of the outside of a blank used in the manufacture of the second form of envelope.

Figure 11 is a plan view of the inside of said blank.

Figure 12 is a perspective view of the blank in Fig. 11, showing it as being ready for enclosure and sealing around a contained article loosely wrapped in a corresponding return blank.

50 Figure 13 is a perspective view illustrating the sealed envelope in Fig. 12 as having been opened at its destination.

Figure 14 is a plan view of a third form of envelope, illustrating the outside of the blank.

Figure 15 is a plan view of the blank in Fig. 14 illustrating the inside.

In carrying out the invention provision is made of a blank 1 which is so designated in all of the forms of the invention excepting that in the second and third forms in Figs. 10 and 14 it is distinguished by the exponent letters *a* and *b*. This blank comprises what has been termed a basic pattern, that is to say, there is no material variation in its formation in any of the three forms. The outside of the blank 1 appears as in Fig. 1. Here the body 2 is shown to have side flaps 3 and 4 which are bendable on scores 5, 6. It also has end flaps 7, 8, these being bendable on scores 9, 10. It is important to observe that the scores 5, 6, are approximately at thirds with respect to the length of the blank 1. The advantage and purpose of this provision is that the two flaps 3, 4 will fully overlap each other in the finally folded envelope 11, the development of which is to be traced through Figs. 4 and 5.

The body 2 of the blank 1 is rectangular in shape. Said body is delineated by the scores 5, 6, 9 and 10. The side flaps 3, 4, are substantially rectangular in shape, but they depart from that configuration by end reductions at 12 which narrow the side flaps by the extent of the reductions and produce offsets 13 which merge into the boundaries of the end flaps 7, 8 as well seen in each of Figs. 1 and 2. Said end flaps are desirably of curvi-linear form although they could be shaped otherwise than illustrated without affecting their intended purposes.

It is to be observed that the scores 5, 6, 9, and 10 terminate at the boundaries of the flaps 7, 8. In doing so they cross at the points commonly designated 14. Said scores flare as the consequence of said crossing, and the flares demarcate fillets 15 which serve the important purposes of reinforcing the body and flaps when the contents of the envelope are thin and providing for the necessary expansion of the envelope when the enclosure is thick. The scores 9 and 10 are located on the end flaps 7 and 8 in lines which are located outwardly of and parallel to a line passing through a pair of end edges of the side flaps at each side of the blank 1.

Reverting to the structure of the blank 1 (Fig. 1), the side flap 3 has a line of perforations 16 which follows the outline of the free edge of the flap, starting and ending at master perforations 17 from which the line 16 branches off to the edges of the flap 3 on slight inclines as at 18.

The flap 3 has an opening 19 cut into it. This opening is covered by a transparent strip of paper 20 (Fig. 2) completing a window. Stamp positions for first, third or fourth class postage are imprinted at 21 and 22 on the outside of the flap 3. The outside of the flap 4 is marginally gummed at 23. A circle 24 or a figure of some other preferred design, is imprinted on a portion of the gummed margin, being supplemented with the notation "Moisten this spot."

On the inside of the blank 1 the body 2 is imprinted with a stamp position 25 and appropriate rulings 26 to guide the writing in of addresses. The margin 27 delineated by the perforations 16 is gummed. This gum is herein known as the sending gum as distinguished from 23 which is the returning gum.

The envelope 11 (Figs. 4 and 5) is adapted to enclose a first class item of mail or a third (or fourth) class item, and then allow for a return response by first class mail. In order to achieve these purposes the blank 1 is used as follows:

The end flaps 7, 8, are first folded inwardly (Fig. 3) upon the body 2 at the scores 9, 10. An item of third class mail, such as a piece of merchandise, may first be laid upon the body 2 whereupon the flaps 7, 8, are folded thereover as stated. The alternative would be to do all of the folding first and then pull out one of the end flaps 7, 8, for the insertion of the article of merchandise.

But continuing with the folding, the next step consists of bringing up the side flap 4, folding the latter on the score 6. The returning gum 23 which formerly was underneath (Fig. 2) is now brought to view. The final fold consists of bringing the side flap 3 down (Fig. 5), the folding being done on the score 5. Previously to folding the flap 3 over the sending gum 27 is moistened carefully from beginning to end. The end portions 28 of it (Fig. 4) will be superimposed upon most, but not all, of the end portions 29 of the returning gum. The side portion 30 of the sending gum will be permanently affixed on top of the flap 4, the result being that the flap 3 is secured to the flap 4 the full extent of the sending gum 27. Only that portion of the returning gum 23 designated by the circle 24 is moistened. This is done separately first, then held to position after which sending gum is moistened and affixed. All of 28 remains unmoistened until contacted in part by the moist portions of 27. As the result of this mode of folding and securing the blank 1 the completed envelope 11 (Fig. 5) is a well sealed receptacle for first class mail immediately beneath the flap 3 and a receptacle for a lower class of mail between the body 2 and flap 4. The first class item of mail is intended to be of the type having an address thereon which will show through the window 9, 20. Postage stamps of the proper denominations are affixed at 21 and 22.

Upon the arrival of this envelope at its destination the recipient should read the instructions which will be printed on at a convenient place. Said instructions will state that a tearing implement, such as the point of a pencil, should be inserted at the master perforations 17 (Fig. 5) and moved along the line of perforations 16. The result will be a separation of the flap 3 from its now adhering margin 27. By swinging the flap 3 back on the crease 5 the first class item 31 will be revealed. The lower class item may be withdrawn either from between the body 2 and flap 4 or from one of the ends of the envelope by first merely pulling out one of the end flaps 7, 8.

Said flaps are capable of being pulled for postal inspection, inasmuch as they are merely loosely held in place. It is this accessibility to the article of merchandise which characterizes it as being of lower class mail. It is now presumed that the addressee wishes to respond to the letter 31. In folding the flap 3 back (Fig. 6) the adhesion at the circle 24 is broken merely by pulling the flap 3 hard enough. The other flaps are then flattened out and turned over as in Fig. 7. The appearance of the blank 1 then is much the same as in Fig. 1 excepting for the adhering portion 27 of the flap 3 outlined by the sending gum.

The flaps 3, 7, and 8 are again folded inwardly (Fig. 8) this time upon the outside of the blank instead of the inside (Fig. 3) the final act being to bring the flap 4 over and down (Fig. 9).

Fig. 7 well illustrates those portions of the returning gum 23 which were not moistened in the first sending. These portions are now moistened after the recipient of the item of mail has enfolded his response under the flaps 3, 7 and 8 (Fig. 8), and the flap 4 is pressed down as already

stated in connection with Fig. 9. Enough of the returning gum 23 is exposed to the flaps 3, 7 and 8 to insure a thorough sealing which will classify the envelope in Fig. 9 as first class mail.

Very often the lower class kind of mail intended to be conveyed by the accessible compartment between the sealed and overlapped side flaps 3, 4, is of a more or less bulky character. It is for the accommodation of an item such as this that the fillets 15 serve as expansion members. Instead of the folds occurring on the creases 5, 6, and 9, 10, they will extend out farther in each of the four directions and thus take in more of the fillets 15. The closure will be just as good as in the first instance because there is enough surplus material in the fillets 15 to compensate for the increase in bulk in the lower class item.

Reference is next made to the second form of the invention in Figs. 10 to 13. The blank 1a is much the same as the blank 1 (Fig. 1). In order to avoid the duplication of the description of corresponding parts in Fig. 1 said parts are identified by corresponding reference numerals but distinguished in the second form by the exponent letter *a*.

Other differences are as follows: The side flap 3a has a margin of sending gum 27a (Fig. 11) which in this instance is not demarcated by a line of perforations as in Fig. 1. Instead of this the flap 3a has an arcuate line 32 of perforations extending from end to end, said line constituting the starting place for two short curved branches 33 which terminate at the contiguous edge of the side flap 3a. The resulting sub-flap 34 is provided with a hole 35 adapted for postal inspection. The arcuate line 32 has master perforations 17a as before, constituting starting places for tearing.

This particular envelope is intended to include in its combination an enclosure 36 (Fig. 12) which consists of a wrapper 37 identical in every respect with the blank 1a. The similarity will be seen by the corresponding reference numerals directed to the arcuate and branch perforations 32, 33. The wrapper 37 is to be regarded as being put around an article of merchandise which is to be submitted to the addressee. Said article, together with its wrapper 37 constitutes the enclosure 36 referred to. The recipient is thus provided with an unmutilated return envelope.

Inasmuch as the enclosure 36 is of appreciable thickness the corner fillets 15a will function fully in the manner previously described in conjunction with the first form of the invention. Having emplaced the enclosure 36 the end flaps 7a, 8a, are folded over whereupon the side flaps 4a, 3a, are overlapped in succession. The flap 3a is sealed by means of the sending gum 27a and by moistening the circle at 24a so that when the unit is complete for mailing it will look much on the order of the envelope 11 in Fig. 5.

The recipient will tear the flap 3a usually along the arcuate line of perforations 32 so that the freed part of the flap 3a can be lifted as in Fig. 13. The enclosure 36 will then be accessible as will also the letter 38. In order to have full access to the letter compartment the branch perforations 33 may also be torn so as to enable laying back the sub-flap 34. By folding the flap 3a down first, followed by flaps 7a, 8a and finally by flap 4a the entire envelope becomes first class.

The third form of the invention appearing in Figs. 14 and 15 comprises a blank 1b which is basically the same as the blank 1 in Fig. 1. Corresponding reference numerals are used through-

out being distinguished in Figs. 14 and 15 by the exponent letters *b*. This particular blank is more in the nature of a business reply envelope, to which end the body 2b (Fig. 15) is imprinted at 39 in the manner generally suggested in Fig. 15. A simple inspection hole 40 is cut in the flap 3b, allowing for postal inspection relative to whether or not said compartment contains any matter at all; as if and when the envelope be mailed strictly third or fourth class. As in each of the other two forms of the invention the blank 1b (Figs. 14 and 15) is intended to be reversed by the recipient of the original item of mail. It is then that the business reply side 39 of the envelope will show.

In conclusion, this invention need not be limited to use in the mails, but when made of suitable material can be used for the enclosure of articles usually shipped by freight or express from factory to showroom, removed from the wrapper for display purposes or otherwise, and again shipped to the consumer in the same reversed envelope. From the foregoing description it will be apparent that the envelope blank lends itself to a number of uses. By an extension of this idea it is possible to obtain other forms merely by altering the positions of one or the other or both end flaps relative to the side flaps.

I claim:

1. An envelope comprising a body having oppositely directed side flaps, the body and flaps being of substantially the same dimension in the longitudinal direction of the envelope thereby to fully overlap the flaps upon themselves and mutually upon the body, gummed margins following substantially the entire boundaries of both side flaps but being located on opposite sides of the respective flaps so as to confront each other in respect to the overlapped side flaps, the entire gummed margin of one of the flaps being secured to the companion flap and to a part only of its gummed margin thereby leaving an unused gummed portion on said companion flap but at the same time defining a closed compartment for first-class mail, and lines of perforations adjacent the aforesaid entire gummed margin of said one flap, including at least one master perforation providing a starting place for tearing along the line of perforations, thus again releasing said one flap for reuse in resealing by employment of the unused gummed portion of said companion flap after reversing the envelope.

2. An envelope comprising a body having oppositely directed side flaps, the body and flaps being of substantially the same dimension in the longitudinal direction of the envelope thereby to fully overlap the flaps upon themselves and mutually upon the body, gummed margins following substantially the entire boundaries of both side flaps but being located on opposite sides of the respective flaps so as to confront each other in respect to the overlapped side flaps, the entire gummed margin of one of the flaps being secured to the companion flap and to a part only of its gummed margin thereby leaving an unused gummed portion on said companion flap but at the same time defining a closed compartment for first-class mail, lines of perforations adjacent the aforesaid entire gummed margin of said one flap, including at least one master perforation providing a starting place for tearing along the line of perforations, thus again releasing said one flap for reuse in resealing by employment of the unused gummed portion of said companion flap after reversing the envelope, and oppositely di-

rected end flaps at the ends of the body adapted to be overlapped upon said reversed one flap thereby to be included in the resealing of the envelope by use of the previously unused gummed portion.

3. An expansible and reversible envelope for transmitting mail matter of the first, second, third, or fourth class, comprising a body having oppositely directed end flaps, opposite directly side flaps, the body and side flaps being of substantially the same dimension in the longitudinal direction of the envelope, thereby to fully overlap said side flaps upon themselves and mutually upon the body, said side flaps having end reductions contiguous to the end flaps, scores demarcating the various flaps from the body, terminating at the margins of the end flaps, said scores crossing each other and defining offsets adjacent to the end reductions of the side flaps and demarcating fillets, gummed margins at the boundaries of both of the side flaps but located on opposite sides of the respective flaps to form closed compartments for respectively sending and returning two classes of mail matter, said end flaps being adapted for tucking around an article of lower class mail pocketed between the body and the overlapped flap next adjacent, said offsets and fillets providing for the outward displacement of the scores, the other side flap having a series of perforations defining a cutting line for opening the first class mail compartment and to free the side flaps to provide for a reversal of the parts to form a return envelope.

4. An envelope comprising a body having oppositely directed side flaps, the body and flaps being of substantially the same dimension in the longitudinal direction of the envelope thereby to fully overlap the flaps upon themselves and mutually upon the body, virtually identical gummed margins following substantially the entire boundaries of both side flaps but located on opposite sides of the respective flaps, one of said side flaps having lines of perforations adjacent its gummed margins including at least one master perforation, said gummed margins confronting each other in respect to the overlapped side flaps, the entire gummed margin of one of the flaps being secured to the companion flap, said companion flap having a designated moistening place in its gummed margin providing for sealing at that place only

5. To the superimposed one flap, the remainder of the gummed margin of the companion flap being left unused, said one flap being adapted for tearing out along said line of perforations and for tearing away at said gummed place for access to the first class mail compartment defined by said overlapped and sealed flaps.

6. A mailable item comprising an envelope consisting of a body having oppositely directed side flaps with gummed margins on the opposite sides of the respective flaps, end flaps completing the envelope, said body having scores at right angles demarcating the various flaps, said scores being crossed near their terminals to define fillets, and an enclosure completing said mailable item consisting of a wrapper including a body with side and end flaps adapted to enclose an article of merchandise, the foregoing side and end flaps being closed down upon said enclosure, and one of the side flaps having an arcuate line of perforations extending from end to end and branch perforations extending from said line to the side margin of said side flap.

7. A reversible envelope for mailing matter of different classes, blank consisting of a single sheet having a body and oppositely directed side flaps, a pair of oppositely directed end flaps, scores at right angles to each other marking off the end flaps and dividing the blank longitudinally into substantial thirds so that the side flaps are substantially the same dimension in the longitudinal direction of the blank as the body, said side flaps having end reductions beyond which the scores of the end flaps are located, all of the scores terminating at the margins of the end flaps and defining fillets adjacent to said end reductions, and gummed margins along the side extremities and the end extremities of the side flaps, said gummed margins being located on opposite sides of the respective side flaps, said gummed margins when moistened adapted to seal the side flaps together to form a first class mail compartment, the outer side flap having a series of perforations adjacent its gummed margins defining a cutting line for opening the first class mailing compartment and for freeing the side flaps from each other to provide for the reversal of the parts and the formation of the return envelope.

GEORGE E. POWELL.
